TRANSMISSION SYSTEM FOR STATISTICAL DATA

James W. Bryce, Glen Ridge, N. J., assignor to
 International Business Machines Corporation,
 New York, N. Y., a corporation of New York

Application October 19, 1938, Serial No. 235,820

9 Claims. (Cl. 178—2)

This invention relates to transmission systems for statistical data and has for its general object the provision of means for verifying data transmitted from a sending station to a receiving and recording station to determine the accuracy of reception by the receiving station as a condition precedent to the recording of such data at the latter station. One form of such means for verifying the data is disclosed herein, another form being shown in my copending application No. 235,819, and still another form in my co-pending application No. 235,821.

More specifically, the object of the present invention is to provide a remotely controlled data recording system with novel means for checking the accuracy of such data, character by character, as a prerequisite to the recording thereof. Thus, by preventing the recording of a data character at a secondary station until after it has been compared for accuracy with the original data at a primary station, the invention attains the object of avoiding recording of inaccurate data at the remotely controlled recording station.

Another object of the invention resides in the provision of a plurality of novelly arranged comparing circuits both at the sending or primary station and at the receiving or secondary station for effecting verification of the transmission of data.

The object is further to provide a novel transmission system in which a data character transmitted from a first station and received at a second station causes the operation of verifying means at the first station to initiate a repeat transmission of the character from the first station, said repeat character transmission operating verifying means at the second station which in turn controls the operation of a recording means for recording the character at the second station.

According to the present invention, a contact control key at a station A is operated to send out a series of impulses which cause a record card to be fed into punching position at a station B, located at a remote point from station A. A character key is then depressed to print the character at station A, and at the same time to partly condition a comparing means at the latter station. Multiple impulses representing the character as sent to receiving means at station B and there partly condition a second comparing means. The comparing means at station B cooperates with a transmitting means at that station to effect retransmission of the char-

acter to a receiving means at station A to be compared with the original character printed there. If there is any agreement, the comparing means becomes fully conditioned and causes a repeat transmission of the character impulses to station B. In the event of a lack of agreement, which is determinable by visual comparison of the printed characters at station A, an adjust key must be operated to send out control impulses to effect proper adjustment of station B with respect to station A. Assuming, however, that the printed characters at station A agree, then the repeat transmission of the character impulses to station B completes the conditioning of the comparing unit at the latter station. If the system is still in agreement, printing and punching of the character at station B occurs. Should the comparison be in error, an adjust key at station B is depressed to send control impulses to adjust station A with respect to station B. Under no condition may an incorrect character be punched at station B, because of the comparison required prior to the setting up of the punching means.

Further objects of the instant invention reside in any novel feature of construction or operation or novel combination of parts present in the embodiment of the invention described and shown in the accompanying drawings whether within or without the scope of the appended claims and irrespective of other specific statements as to the scope of the invention contained herein.

In the drawings:

Figs. 1 and 1a are representative circuit diagrams of the transmitter and receiver respectively at station A.

Fig. 1b is a timing chart for the circuit diagram shown in Fig. 1.

Figs. 2 and 2a are representative circuit diagrams of the receiver and transmitter respectively at station B.

Fig. 2b is a timing chart of the circuit diagram shown in Fig. 2a.

Fig. 3 is a plan view of a portion of the transmitted key board.

Fig. 4 is a sectional view taken at 4—4 of Fig. 3.

Fig. 5 is a sectional view taken at 5—5 of Fig. 3, showing a transmitting key and the various operating mechanism associated therewith.

Fig. 6 is a view of the dash pot control mechanism which is applied to certain relay contacts in the various circuits of the system.

Fig. 6a is a detail plan view of the mechanism associated with the dash pot.

Fig. 7 is a detail view of a portion of the punching mechanism.

A preferred embodiment of the invention will now be described with reference to the accompanying drawings. At station A a special keyboard is provided as shown in Figs. 3, 4 and 5. Seven keys are shown as representative, three of them being allotted to numerical characters and the remaining four being provided for various control operations such as space control, card feed, verifying, and adjusting. If more than three different numerals are to be transmitted more numeral keys are added, but the four control keys are sufficient regardless of an increase in the numeral keys. Depression of any of the keys causes the operation of a special set of contacts associated therewith so as to initiate a corresponding impulse or series of impulses. If a numeral key is depressed, it also causes printing of the numeral by energizing a print solenoid associated therewith, all of which will be described in detail hereinafter. The mechanism illustrated in Fig. 5 in association with the adjust key 17 is similar to that for the other keys. It is seen that the depression of key 17 causes an insulated conducting portion 17a to bridge the contact springs 17b. A notched projection 17c at the same time cams latch bar 19 to the right and then allows it to return to the left again under spring action so that the left extremity of bar 19 is positioned above the latch point on projection 17c to hold the key down. Then at a later time, as will be described later, solenoid 18 becomes energized momentarily to move the latch bar 19 to the right away from projection 17c, thus releasing the key 17 and allowing it to raise to its normal position under the urging of its return spring 17d. It will be noted that only one key may be depressed at a time due to the presence of locks 9 (Fig. 4). When a key is down it maintains the locks adjacent thereto spread apart so that the combined clearance of the locks 9 is taken up and no other key may be moved down between them. This structure is elementary and similar to that used in key-operated punches to prevent the operation of more than one key at a time so that no further description is believed necessary.

A transmitting commutator 20 (Fig. 1) and a rotatable arm 21 are also located at station A, arm 21 being maintained continuously rotating in a clockwise manner at uniform speed by any suitable means such as an electric motor (not shown). The speed at which this arm is to rotate is determined by two factors; namely, the desired speed of transmission of the impulse and the speed of functioning of the receiver mechanism at station B. As arm 21 traverses the various transmitting segments of the commutator 20, a plurality of circuits are successively closed depending upon which of the keys 11 to 17 was operated to effect the transmission of a predetermined number of impulses from the transmitting device 43. The circuits will be described in detail later.

The mechanism actuated at the receiver of station B by the incoming impulses comprises a chain system of multiple contact relays R1 to R7 (Fig. 2) which control the selective energization of a plurality of print solenoids, such as the one designated 62 for example. Solenoid 62, upon becoming energized, pulls its armature 62a and the key lever connected thereto down so as to operate a printing mechanism which is diagrammatically represented by a platen 57, a hammer 57a, and suitable linkage 57b connected between

the hammer and the key lever. Motion transmitted through the linkage 57b causes the hammer to be moved toward the left to strike the platen. The leftward movement of the hammer closes a contact 62b to energize a punch solenoid 72 by a circuit to be described later. Punching mechanism of any convenient type such as shown in the U. S. Patent No. 1,772,186 to F. L. Lee et al., for example, may be employed. Printing and punching under solenoid control are old in the art, and therefore the representation of the printing and punching means illustrated in Fig. 2 and Fig. 7 respectively are believed sufficient.

In Fig. 7 an interposer 71 is moved to the left under control of a solenoid (not shown) so that as motor bar 78 is moved down sharply on the interposer 71 by the energization of the punch magnet (not shown), the punch 80 will be moved down to pierce the card C. Return springs insure the restoring of motor bar 78, the interposer 71, and the punch 80, and the usual escapement action advances the card C to the next column.

An impulse means comprising a commutator 24 and an arm 25 is provided at station B and there cooperates with a transmitting device 125 to effect the resending of character impulses to station A. A chain system of relays forms a receiving means at station A similar to that already described for the station B receiver. Arm 25 is rotated in a uniform manner by means similar to that for arm 21 but not necessarily at the same speed.

Although the commutators at stations A and B do not run in synchronism, there is a certain time controlled relationship between the receiving portion of each of these stations and the transmitting portion of the other. This comprises a control relay 55 at the receiver of each station having dash pot mechanism generally designated 54 (Fig. 6) associated therewith to control the time of closing of a plurality of sets of contacts including those designated 55b, 55c, 55d, and 55e. Relay coil 55, upon becoming energized attracts the armature 5 so that a cylinder 5a attached to the right extremity of the armature is moved down forcing air out through an opening 7 in the dash pot 54. It is seen that the speed of operation of contacts 55b, 55c, 55d, and 55e are dependent upon the size of the opening 7 which is adjustable in a manner to be explained presently. When the relay coil 55 is deenergized, the outside air rushes in through the opening 8 and the armature is allowed to restore quickly under spring action and return the above contacts to their normal position.

The size of the opening 7 is manually adjustable by turning knob 6' which is fixed to a threaded shaft 6. Automatic means for rotating the shaft 6 in either direction is also provided so as to speed up or slow down the closing of the contacts under control of the dash pot mechanism. A train of gears, generally designated 4, connects the shaft 6 for operation by a differential device 66 actuated by a pair of pawls 91, 92 and ratchets 66a, 66b. The shaft 6 forms a frictional mounting for one of the gears of the above train. The ratchets may be locked or released according to the position of a pair of cooperating detents 2 and 3. The detents are normally in the position shown in the drawings and are mounted on a common shaft 1. A solenoid X controls the engagement and disengagement of the detents. When detent 2 is disengaged from ratchet 66a, detent 3 is engaged in ratchet 66b. A magnet 135, when energized, causes the pawl 91 to feed ratchet 66b clockwise one tooth. A magnet 136 cooper-

ates with pawl 92 to feed ratchet 66a counterclockwise one tooth. The manner in which these magnets are energized will be better understood later from the description of the circuits of the system. It is sufficient for the present to state that the stepping of ratchet 66b in a clockwise direction causes the threaded shaft 6 to back up by motion transmitted thereto through the gear train 4 and allow an increase in the size of opening 7. On the other hand, the counterclockwise movement of ratchet 66a causes motion to be transmitted through the gear train 4 to turn shaft 6 clockwise thereby decreasing the size of the opening 7. Thus, ratchet 66b is operated in the direction indicated by the arrow to speed up dash pot action and ratchet 66a is operated to slow down this action. The solenoid X is located in series with magnet 136 and is energized when the latter is energized so as to release the ratchet 66a. Ratchet 66b is normally free of detent 3 so that solenoid X need not be operated upon the operation of magnet 135. The purpose of the dash pot control mechanism and the automatic adjustment therefor will be explained in connection with the explanation of the circuits and operation of the system which now follows.

At the start it is assumed that the printing means comprising two typewriters at station A and one at station B have paper inserted therein and that the punch at station B has a pack of fresh record cards in its hopper, and that the two stations are in adjustment which is described later. It is first necessary to feed a card from the hopper between the die and stripper of the punch to a punching position. This is accomplished by transmission of a predetermined number of impulses from station A to station B. These impulses cause the energization of a selected control magnet of the chain relay system already described which in turn causes the punch clutch magnet to be energized in a manner to be described presently. A key 15 (Fig. 1), referred to as the card feed key, is depressed (see Fig. 5 and Fig. 1) to initiate the above operation.

The depression of the card feed key 15 causes conducting portion 15a to bridge contact springs 15b and complete a circuit to connect relay coil 35 directly across the line. Relay 29 also becomes energized by a circuit from right hand side of the line 27, contacts 150a in their normal position, wire 28, contacts 35a now closed, relay coil 29, to left hand side of the line 26. Relay 29, when energized, closes its contacts 29a which in turn complete a circuit to energize clutch magnet 40 as follows: right hand side of the line 27, contacts 29a now closed, clutch magnet 40, to left hand side of the line 26. The energization of magnet 40 causes the cam associated with contacts CC-3 to be clutched in for rotation with the same shaft which carries arm 21. Cam CC-3 therefore now rotates in synchronism with the arm 21 from the D position onward. Near the end of the next cycle, the cam causes the closure of its contacts CC-3 for a purpose which will be explained later. It might be well to mention here that the depression of any of the keys 11 to 17 causes the clutching in of the CC-3 cam to the commutator shaft and the energization of relay coil 29.

The energization of relay 35 upon depression of the card feed key 15 causes the closing of contacts 35a and 35g. A circuit is completed through contacts 35a at the time arm 21 contacts segment 20a of the commutator 20 in the following manner: from line 27, contacts 150a

in their normal position, wire 28 to contacts 35a now closed, relay coil 30, contacts 39b, commutator segment 20a, arm 21, to line 26. Relay coil 30, upon becoming energized by the above circuit, closes its contacts 30a to cause the energization of relay coil 38 from line 27, contacts 30a, relay coil 38, to line 26. The holding circuit for relay 38 is through contacts 38a now closed and cam contacts CC-1. As previously mentioned, the CC cams are driven at the same speed as arm 21, and when the arm 21 is at line D of commutator 20, the CC cams are in the well-known D position as illustrated in the timing diagram (Fig. 1b). Relay 38 is provided with contacts 38b which are located in series with the transmitter 43 and are normally open. Thus, it is seen that transmission may be effected only when the energization of relay coils 30 and 38 has occurred previous to the passage of arm 21 over the various transmitting segments of the 20 commutator 20.

With relay 38 energized, a series of impulses may now be transmitted. The transmitting circuit is from line 27 through resistance 41, contacts 38b now closed, wire 42, contacts 35g now closed, relay coil 45, segment spot 20b, arm 21, to line 26. The flow of current through resistance 41 causes a potential drop across it which is impressed upon the input of the transmitter 43 to cause an impulse to be sent out from station A to station B. Relay 45, upon being energized by the previously traced circuit, closes its contacts 45a to energize relay coil 44 from line 27, through relay contacts 45a, through relay coil 44, to line 26. Relay coil 44 is then held energized through its contacts 44a and cam contacts CC-2 until the end of the transmitting period (see timing diagram, Fig. 1b). As the rotating arm 21 successively contacts the segment spots 20c, 20d, 20e, and 20f, additional impulses are sent out from transmitter 43. In this case, that is, where key 15 is depressed, the contacts 35c through 35g cause transmission of impulses, five in number. Assuming the key 15 has been released by the operator, it is still held in a down position by latch 19 in a manner already described for key 17.

Following the transmitting portion of the cycle, a circuit is completed to energize relay coil 39 by means of the arm 21 from line 26, through arm 21, through segment spot 20n, through contacts 44b now closed, relay coil 39, to the other side of the line 27. Relay coil 39 is held energized through its contacts 39a and relay contacts 29b now closed. The energization of relay coil 39 by the above circuit opens its contacts 39b and prevents energization of the relay coil 30 should the key 15 remain depressed for another machine cycle. This effectively prevents transmission of a repeated series of impulses for the same depression of the key. Key 15 is released near the end of the cycle when cam contacts CC-3 close to energize relay 18, which shifts latch 19 (Fig. 5) to permit key 15 to move upward under spring action in the same manner as illustrated for key 17. If the operator, however, has not yet released key 15, the shifting of latch 19 has no effect and magnet 40 remains energized due to continued closure of relay contacts 29a. Once the operator removes pressure from the key, however, the next shifting of latch 19 will release key 15 thereby deenergizing relay coil 29 and consequently relay coil 39. Relay contacts 39b then are allowed to close once more and, upon the next key depression, a new series of impulses may be transmitted.

The five impulses transmitted in the manner just described are received at station B and effect a card feed there as follows: Upon reception of each impulse at station B (Fig. 2) the receiver 50 is actuated accordingly and causes the energization of relay coil 52 for each impulse. Coil 52 closes its contacts 52a upon each energization. The first impulse completes a circuit from line 46, relay contacts 52a now closed, 10 through center and upper relay contacts 51a, R1b, R2b, etc., through R1b, wire 49, relay coil 51, and back to the other side of the line 47. Relay coil 51 then shifts its "make before break contacts" 51a, that is, the center and lower contacts make before the center and upper break. Coil 51 thus remains energized for the duration of the first impulse through relay coil 52. Contacts 51b close and cause the energization of relay coil R1 from the left-hand side of line 46, 20 through contacts 53a, contacts 51b, contacts R1a, relay coil R1, to line 47. Relay coil R1 is maintained energized through contacts R2d, the holding circuit being from line 47, relay coil R1, transferred contacts R1a, relay contacts R2d, contacts 25 53a, to line 46. The contacts R1a are also of the "make before break" type. Relay contacts 51c also close to cause the energization of relay coils 55 and 55' by completing a circuit from line 47, relay coils 55 and 55' in parallel, contacts 51c 30 now closed, to line 46. The holding circuit for these coils is through contacts 55'a, 60, 61, 53b, and 63a.

A plurality of contacts are operated under the control of relay coils 55 and 55'. Those operated by coil 55, including contacts 55b, 55c, 55d, and 55e, are provided with dash pot control mechanism as already described. Contacts 55'a and 55', which are operated by relay coil 55', are not dash pot controlled. The purpose of the dash pot is to prevent any one of the chain relays from being energized to effect control until the completion of the time during which all possible signal impulses have entered the chain relay group. Accordingly, the adjustment of the dash pot is such that contacts 55b do not close until the arm 21 at station A has contacted the segment spot 28m. The adjusting circuits will be explained later.

The next impulse which enters the chain relay group causes the energization of relay coil R2 by the following circuit: from line 46, relay contacts 52a, relay contacts 51a in the position shown, relay contacts R1b in a transferred position, relay contacts R2d, relay coil R2 55 in the position shown, to line 47. Relay coil R2, upon being energized, shifts its a, b, c and d contacts. The shifting of the R2d contacts, which are of "make before break" type previously described, transfers the holding circuit for relay R1 back through contacts 52a. Therefore, upon opening of these contacts, relay R1 is deenergized. Relay R2 is held energized through contacts R2a and R3d. In a similar manner each successive impulse entering the chain causes an energization of a new relay and deenergization of the previous one. When the five impulses representative of a card feed are all received, relay R5 is energized to manifest this fact. Shortly thereafter relay contacts 55b close 65 and a circuit is completed as follows: from line 46, relay contacts 55b, switch 56 now closed, contacts R1c, R2c, R3c, and R4c in the position shown, contacts R5c now in a shifted position, solenoid 67, to line 47. This circuit energizes solenoid 67 causing it to pull down its plunger 67a and to

close its contacts 67b. The closing of contacts 67b completes a circuit to energize relay coil 68 as follows: from line 46, relay coil 68, contacts 67b, to line 47. The depression of plunger 67a also closes contacts 67c causing relay coil 53 to become energized by a circuit from line 47, contacts 67c, relay coil 53, to line 46. Relay coil 53, upon energization, opens its contacts 53a to deenergize relay R5, and also opens its contacts 53b to deenergize relay coil 55. With the energization of relay coil 68, contacts 68a close to complete a circuit from line 46, through contacts 68a, through the punch clutch magnet 70 and back to the right-hand side of line 47. Energization of punch clutch magnet 70 shifts contacts 69 to energize the punch motor 65 by completing a circuit thereto from the left-hand side of line 46, through contacts 69, through motor 65, and back to line 47. The punch motor 65 then operates to effect the feeding of a new record card 20 to the punching position.

Station B is now ready to receive the impulses representative of statistical data from station A. One of the digit keys at station A, for example, key 12 (Fig. 1) is now depressed and closes its 25 associated contacts 12b in a previously described manner to effect the energization of the relay coil 32. The closure of contacts 32b then completes a circuit from line 26, through contacts 32b now closed, through typewriter solenoid S2 and back 30 to the right-hand side of line 304. Energization of solenoid S2 causes printing of the numeral 2 at station A. Closure of contact 32a causes a pickup of relay 30 and also relay 38 as previously described so as to prepare the transmitting circuit. Closure of contacts 32c and 32d then permits transmission of two impulses from station A to station B, the transmission of these impulses being effected in the same way as for the card feed impulses. The energization of coil 40 32 as described above also brings about the energization of a comparing relay 202 (Fig. 1a) which is one of a group of relays forming a comparing unit at station A. The circuit is from line 46, contacts 32e now closed, relay coil 202, 45 conductors 22 and 23 to line 47.

At the completion of the transmitting portion of the cycle, arm 21 (Fig. 1) engages segment 20s to complete a circuit from line 26, arm 21, segment 20s, contacts 38c now closed, relay 50 coil 167, to line 27. Coil 167 is maintained energized through parallel contacts CC-5 and 160b. Contacts 167b close to provide a circuit to connect relay coil 160 with commutator segment 20r as follows: from line 27, relay coil 160, contacts 55 38d now closed, contacts 167b, to commutator segment 20r. The latter circuit is not completed to the other side of the line at this time, since arm 21 has already passed segment 20r. This circuit functions in conjunction with the comparing relays at station A in a manner to be described hereinafter.

To continue with the example, at station B relay coil R2 becomes energized upon the reception of two impulses from station A and, at the 65 time dash pot contacts 55b close, a circuit is completed from line 46, contacts 55b now closed, receiving switch 56 now closed, contacts R2c in a transferred position, coil 152, to line 47. This circuit energizes the coil 152 which then closes 70 its contacts 152a (Fig. 2a). As a result, a circuit is completed to energize a comparing relay coil 232 as follows: from line 46, contacts 120p now closed, escapement contacts 58', center and lower contacts 248b, relay coil 301, conductor 302, 75

contacts 152a now closed, relay coil 232, to line 47. Contacts 232c then close to energize relay coil 262 by the circuit just traced as far as coil 301, then via conductor 303 to contacts 232c now closed, relay coil 262, to line 47. Upon energization of coil 262, the relay 261 also becomes energized because of the closing of contacts 262a which places coil 261 in parallel with the coil 262. In like manner if three impulses had been received, instead of the two assumed for the example, coil 263 would have become energized and caused both coils 262 and 261 to be placed in parallel with it. The effect of the above relay arrangement becomes apparent from the description of the circuits for retransmitting impulses to station A which now follows.

With relay coils 262 and 261 energized, a circuit is provided when the dash pot relay contacts 55g close to transmit impulses back to station A for verification. Relay coil 108 is energized as arm 25 contacts segment 24j of the commutator 24 by a circuit from line 41, relay coil 108, segment 24j, arm 25, contacts 55g now closed, to line 46. Then, as arm 25 contacts segment 24a, the transmitting circuit is completed as follows: from line 46, contacts 55g now closed, arm 25, segment 24a, contacts 261b now closed, 108b now closed, resistance 112, to line 47. The potential drop created across resistance 112 causes transmission of an impulse from transmitter 125 to station A. The transmitting circuit is again completed when arm 25 engages segment 24b, since contacts 262b are closed, and thus a second impulse is transmitted back to station A.

At the termination of the sending portion of the cycle of commutator 24 and arm 25, the latter engages segment 24f and a circuit is completed through relay contacts 108c now closed, to energize relay coil 248 which, upon becoming energized, is held through its contacts 248a, escapement contacts 58', and contacts 120p. When the relay coil 248 is energized, contacts 248b transfer and thereby break the circuit to the 261, 262, etc. coils and provide a new circuit to the 241, 242, etc. coils which becomes effective at a subsequent time in a manner to be described later. Then, when the arm 25 engages segment 24g, a circuit is provided through contacts 108d, now closed, to energize relay coil 237. Contacts 237a (Fig. 2) close to energize relay coil 53. The energization of coil 53 opens contacts 53a, 53b and thereby deenergizes relay coils R1, R2 and 55, 55'.

At station A, the two impulses sent from station B are received in the same manner already described for the receiving of the original two impulses at station B. Thus, relay R2 at station A is energized (Fig. 1a) and, when contacts 55b close, the energization of coil 172 is effected currently with the energization of typewriter solenoid S'2 by a circuit from line 46, contacts 55b now closed, receiving switch 56, Ric contacts in their normal position, contacts R2c now transferred, relay coil 172, solenoid S'2 to line 47. Thus, as a result of solenoid S'2 becoming energized, the character 2 is printed on a second typewriter at station A and the circuit which caused this printing also causes the closing of contacts 172a in the comparing unit at the latter station to bring about the energization of comparing relay coil 212. As coil 202 has been energized previously in a manner described hereinbefore, a circuit is completed upon the closing of the 212b contacts as follows: from line 46, relay coil 156, contacts 202b now closed, contacts

212b also now closed, relay coil 222, to line 47. Relay contacts 222a (Fig. 1) close and contacts 150a are shifted upon the energization of coils 222 and 150 by the circuit just traced, and the way is prepared for an automatic repeat transmission of the impulses from station A to station B.

To effect a repeat transmission, one of the relays 31 to 34, in this case 32, is energized by a circuit completed from line 21, contacts 150a in the shifted position, conductor 149, contacts 222a now closed, relay coil 32, to line 46. Contacts 32a to d now close and transmission is effected in conjunction with commutator 20, arm 21, and transmitter 43 in the previously described manner. Thus, two impulses are sent once more to station B. At the completion of this second transmitting operation, arm 21 engages segment 20r and completes the circuit to energize relay coil 160. The circuit was already conditioned for energization by the closing of contacts 167b and 20 38d, as previously described, during the first transmitting operation. Upon energization of relay coil 160, contacts 160a close to provide a holding circuit for this relay in conjunction with cam contacts CC-7, now closed. The energization of relay 160 also effects the deenergization of the comparing relays 202 and 212 because of the opening of contacts 160c (Fig. 1a). Contacts 160b (Fig. 1) also open and, when cam contacts CC-5 open, the circuit to relay coil 167 is broken. 30

Considering now the second reception of the impulses at station B, relay R2 (Fig. 2) and coil 152 are again energized in the usual manner and, with contacts 248b (Fig. 2a) now shifted, contacts 152b close to complete a circuit to energize a comparing relay coil 241. This circuit is from line 46, contacts 120p, escapement contacts 58', contacts 248b in their shifted position, relay coil 300, contacts 152b now closed, relay coil 242, to line 47. As relay 232 was energized on the first reception of the impulses, when relay 242 becomes energized a circuit is completed from line 46, contacts 232b and 242b, both now closed, relay coil 252, to line 47. The circuit just traced energizes the coil 252 so that contacts 252a (Fig. 2) are closed to energize an interposed solenoid 62 to cause the punching of a "2" hole in the record card C in the usual manner. The punching operation causes a shift of the escapement contacts 58' (Fig. 2a) to deenergize the comparing relays 232 and 242, and also relay 248.

If there is a lack of verification at station B on the second transmission, the error will be manifested in the following manner. The original transmission of impulses from A to B energizes relay 301 temporarily, as already explained, during the energization of comparing relay 532. Contacts 301a close to energize relay coil 304 by a circuit from line 47, coil 304, contacts 301a now closed, conductor 307, to line 46. A holding circuit is now established for relay 304 from line 47, contacts 304a now closed, contacts 120m, through a series parallel arrangement of normally closed contacts of the comparing relays 231 to 234 and 241 to 244, conductor 307, to line 46. The repeat transmission of impulses from A to B causes relay 300 to become energized momentarily during the pickup of the comparing relay 242. When contacts 300a close, relay 305 is energized in a manner similar to that described for relay 304. 70 Relay 305, however, may or may not be held energized through the series parallel circuit of comparing relay contacts, depending upon an agreement or lack of agreement between the first received impulses and the repeat impulses. Thus, 75

where relays 232 and 242 are energized by the respective sets of impulses, there is an agreement and a parallel portion of the holding circuit is opened to deenergize both relays 304 and 305. In the event that there is a lack of agreement, for example where 232 and 243 are energized, the relays 304 and 305 will remain energized, and contacts 304b and 305b complete a circuit to energize a bulb 310 which may be in the form of a red indicating light. If this light is energized and remains energized, it is an indication at station B that the system is in error. Accordingly, an adjust key 104 is depressed at station B to effect the sending of adjusting impulses to station A in a manner to be described hereinafter. Relay coil 128 becomes energized and is held energized through contacts 128a now closed, and contacts CC-6 and 138d in parallel. Contacts 128m open to drop the holding circuit to coils 304 and 305, and contacts 128p open to deenergize coils 248 and 232, 242, thus restoring the B station to its normal receiving condition.

When it is desired to space between characters, the space key 14 (Fig. 1) is depressed to send out four impulses to station B, there to energize relay R4 in the usual manner. The comparing unit at each station checks these four impulses by the same method which was described for character transmission before permitting space 30 solenoid 94 to become energized to space the typewriter. A solenoid 100 then becomes energized as contacts 94b close to space the record card in the punch.

It is to be especially noted in the above description that a double comparison is made for each character transmitted before that character is permitted to be punched in a record card. The first comparison is effected at station A where the retransmitted character impulses from 40 station B are compared with the original character impulses. This comparison is visual, that is, by an observation of the printing of the character by the two typewriters at stations A. Then, the second comparison is made at station B when 45 the repeat transmission character impulses are compared with original character impulses received at that station. The second comparison for accuracy must show an agreement, otherwise a red signal is made to glow at station B.

50 In starting operations and at various times, such as when the comparing units show a lack of agreement, it becomes necessary to adjust the dash pot controls at both of the stations to insure proper timing of certain circuits associated with 55 the receiving chain of relays. The present transmission system requires one or more of a series of impulses to effect transmission of statistical data as already described. Each impulse of this series energizes a corresponding relay and causes deenergization of the one just preceding it. Because of this the last relay energized is representative of the transmitted signal, and no relay must become effective until the time for picking up the last relay in the group has been passed. This timing is effected by dash pot controlled 60 relay contacts, the adjustment for which will now be described.

These contacts at station B which are dash 70 pot controlled must close within a period determined by the speed of rotation of the transmitting commutator at station A. That is, the first of a series of impulses triggers off the dash pot relay 55. The contacts controlled by this relay 75 must not function before the time has passed

when the last possible transmitting signal impulse might be received from station A.

Therefore, since the first impulse from station A triggers off the dash pot relay at B, if the time of closure of these points is checked by an additional impulse following the time of signal impulses, it is possible to determine if the adjustment is correct or not on the dash pot relay. Means is provided to automatically effect correct adjustment at station B by the signal of adjustment from station A and likewise station B to A. For the machine to be in adjustment, the contacts 55b must close following the completion of the signal impulses and while the arm 21 at station A is contacting segment spot 20m.

When starting up sending operations, for example, each morning prior to beginning transmission, the operator at station A begins the adjusting operations. Operator at station A depresses the adjusting key 17 and operator at B opens receiving switch 56 prior to adjusting to prevent printing. Depression of key 17 effects the transmission of seven impulses to station B and energization of relay R7 at this station in the customary manner. Sets of contacts 55c, 55d, and 55e are operated concurrently with contacts 55b for testing the adjustment, and contacts 55f concurrently with 55'a. The segment spot 20m which is used for adjusting purposes is longer than any of the other segment spots. This 30 is to hold relay R7 energized for an appreciable period and allow some tolerance in the adjustment of the dash pot relay. Relay R7 is not provided with the usual holding circuit through contacts at station B. Hence, relay R7 is energized 35 only while the arm 21 contacts segment 20m. If contacts 55c close while relay R7 is energized, the dash pot (Fig. 2) control is in adjustment and a circuit is completed as follows: Line 46, relay contacts 55c now closed, relay contacts R7e 40 now closed, contacts 131c, coil 133, to line 47. Relay 133 upon energization is held energized through its points 133a and relay contacts 81d and 128r. Relay contacts 133a, in closing, light a green lamp in the holding circuit which informs the operator at station B that his machine is in adjustment. Also, relay 63 is energized to open its 63a contacts and drop relay 55. Operator at B would then begin sending an adjusting impulse to station A to operate similar circuits 50 at the latter station in a manner to be described shortly.

If the dash pot control at station B is too rapid, the sequence of events is as follows: The contacts 55e become closed before the adjusting impulse opens contacts R7g and relay coil 131 is energized by a circuit from line 46, contacts 55e, contacts R7g, relay coil 131, to line 47. Relay coil 131 is held energized through contacts 131a and contacts 81d and 128r. Contacts 131b close 60 to energize relay coil 132 when R7g closes, coil 132 being then held through contacts 132a, 81d and 128r. Relay contacts 132a, in closing, light a red lamp in the holding circuit to show that the adjustment is not correct.

If the dash pot control at station B is too slow, contacts R7g open and close before contacts 55d open and thus relay coil 134 is energized. Also, coil 131 is energized, but coil 132 is not energized at this time. A red light in the holding circuit 70 indicates machine is still out of adjustment. The energization of coil 134 automatically effects an adjustment of the dash pot mechanism to speed up the relay action by closing points 134b and energizing the adjusting magnet 135 (Fig. 2a) 75

which causes shaft 6 (Fig. 6a) to rotate counter-clockwise to effect a speeding up of the dash pot action by increasing the size of the opening 7 as has been previously explained. Closure of 132b 5 points energizes magnet 136 to slow up the dash pot action by causing a clockwise rotation of shaft 6.

To transmit an adjusting impulse from B to A the adjust key 104 is depressed to energize relay 10 coil 120 (Fig. 2). Relay 120 is then held through its contacts 120a and normally closed contacts 138d in parallel with CC-6. The 120e contacts (Fig. 2a), in closing, cooperate with the shifting of contacts 120b to provide a circuit for picking 15 up relay coil 138 when arm 25 contacts spot 24j. The 138b contacts then close to provide for transmitting the adjusting impulses through the contacts 120f, g, h, k, m, and the transferred contacts 120c and d. An impulse circuit may be 20 traced as follows: from line 47, contacts 120d in a shifted position, resistance 112, contacts 120c in a shifted position, contacts 138b now closed, contacts 120f, 120g or 120h, etc., now closed, corresponding commutator segment 24a, 24b, or 25 24c, etc., arm 25, contacts 120e to line 46. The last impulse occurs when arm 25 is on segment 24e and effects adjustment at A in a manner similar to that already described for station B.

The operator at A seeing his adjusting lights 30 flashing knows station B is in adjustment, and that he may discontinue transmission of his adjusting signal to station B. Station A being in adjustment, the operator there sends back a single adjusting impulse to station B which indicates this fact to the B operator. The relays 35 131-134 are deenergized either upon the next incoming signal, at which time relay coil 51 is energized and opens its 51d points, or when contacts 120r open upon sending an adjusting signal. Relay coil 120 (Fig. 2) is held energized 40 through contacts 138d and CC-6 in parallel. Contacts CC-6 close before coil 138 is energized to open its contacts 138d, but contacts CC-6 open before contacts 138d reclose upon deenergization of 138, and relay 120 is dropped at this time.

Relay coil 55 becomes deenergized when the solenoids 135 or 136 shift their associated ratchet arms 91 and 92 so as to open contacts 60 or 61. 50 When the adjustment is correct, pickup of relay coil 63 (Fig. 2) opens 63a (Fig. 2a) to drop coil 55. While coil 63 is energized the holding circuit of coil 55 is open, and it is necessary therefore that coil 51, when energized, remains in its 55 operated condition long enough to drop coil 63. Coil 51 is then deenergized in a previously described manner and its contacts 51c close to pick up coil 55 once again.

While there has been shown and described and 60 pointed out the fundamental novel features of the invention as applied to a single modification, it will be understood that various omissions and substitutions and changes in the form and details of the device illustrated and in its operation 65 may be made by those skilled in the art without departing from the spirit of the invention. It is the intention therefore to be limited only as indicated by the scope of the following claims.

70 What is claimed is:

1. In a data recording and checking system, a transmitting station including therein means to transmit multiple primary impulses representing digit values, and a primary value checking means 75 partly conditioned by and in accordance with

the first operation of the transmitting means; in combination with a remote receiving and recording station having therein means responsive to the transmitted impulses, a secondary value checking means partly conditioned by and in accordance with the operation of the impulse responsive means, return impulse means controlled by the partly conditioned verifying means for returning secondary impulses representing the digit value to the transmitting station to complete the conditioning of the primary value checking means for checking the values represented by the secondary impulses with the values represented by the primary impulses, means controlled by the fully conditioned primary checking 10 means for effecting a second operation of the transmitting means to send primary impulses again to the receiving station to cause the full conditioning of the secondary checking means, and perforating means at the receiving station 15 rendered effective by the fully conditioned secondary checking means, means for recording the digit values on a record at the receiving station.

2. In a data recording and comparing system, a transmitting station including therein primary 20 means to transmit multiple impulses representing a data character, a primary data comparing means partly operated by and in accordance with the first operation of the transmitting means; in combination with a receiving station having 25 therein means responsive to the transmitted impulses, a secondary data comparing means partly operated by and according to the operation of the impulse responsive means, a secondary sending means controlled by the partly operated secondary 30 comparing means for sending secondary impulses to the transmitting station to complete the operation of the primary data comparing means for comparing the data character represented by the secondary impulses with the data 35 character represented by the primary impulses, means controlled by the fully conditioned operated primary comparing means for initiating a second operation of the primary transmitting means to send primary impulses again to the 40 receiving station to complete the operation of the secondary comparing means, and perforating devices at the receiving station selected for operation by the fully operated secondary comparing means for perforating the data character on a 45 record.

3. In an item recording and matching system, a transmitting station including therein primary 50 means to transmit a series of impulses representing an item, and a primary item matching unit 55 comprising a plurality of pairs of companion relays, one of said relays being energized as an incident to and in accordance with the first operation of the transmitting means; in combination with a receiving station embracing therein means responsive to the transmitted impulses, a secondary item matching unit also comprising a plurality of pairs of relays, one of the latter relays being energized as an incident to and in accordance with the operation of the impulse responsive means, a secondary sending means controlled by the energized relay of the secondary matching unit for sending a series of secondary impulses representing the item to the transmitting station to energize the companion relay of the previously energized relay of the primary matching unit, means 60 jointly controlled by the energized relays of said primary matching unit for effecting a second operation of the transmitting means to send a primary series of impulses again to the receiving 65 station.

- station to energize the companion relay to one previously energized in the secondary matching unit, perforating devices at the receiving station for perforating the item in a record, in accordance with the operation of the impulse responsive means, and means jointly controlled by the energized relays of said secondary matching unit for rendering the impulse responsive means effective to cause operation of perforating means.
10. 4. In a data recording and verifying system, a transmitting station including therein means to transmit primary impulses corresponding to data, and a primary data verifying means partly operated by and in accordance with the first operation of the transmitting means; in combination with a receiving station having means responsive to the transmitted impulses, a secondary data verifying means partly conditioned as an incident to and in accordance with the operation of the impulse responsive means, means including means to send secondary impulses corresponding to the data to the transmitting station under the control of the partly operated secondary verifying means for completing the operation of the primary verifying means, means controlled by said fully operated primary verifying means for effecting a second operation of the transmitting means to send primary impulses again to the receiving station to complete the operation of the secondary verifying means, perforating means at the receiving station for perforating the data on a record, and means rendered effective by the fully operated secondary verifying means for recording the data on a record in accordance with the operation of the impulse responsive means.
15. 5. In an item recording and verifying system, a transmitting station including therein transmitting means to transmit impulses representing a selected item, and a primary comparing unit including a plurality of sets of matching relays, one of said relays being energized as an incident to and in accordance with the first operation of the transmitting means; in combination with a receiving station having therein receiving means for receiving said impulses, a secondary comparing unit also having sets of matching relays, means controlled by the receiving means in accordance with the impulses received for energizing a relay of one of the sets of the secondary comparing unit, means effective upon the energization of the latter relay for energizing another relay of the first comparing unit, means dependent upon whether the two energized relays of the first comparing unit are in the same set or in different sets for determining whether a second operation of the transmitting means is to occur, means effective upon the second operation of the transmitting means for energizing another relay of the secondary comparing unit, and perforating means at the receiving station rendered operative in accordance with the operation of the impulse receiving means in the event that the two relays energized in the secondary comparing unit are in the same set for perforating the item in a record.
20. 6. In an item recording and verifying system, a transmitting station having therein transmitting means to transmit primary impulses representing a selected item, and a comparing unit including a plurality of sets of matching relays, one of said relays being operated as an incident to and in accordance with the first operation of the transmitting means; in combination with a receiving station embracing therein a receiving means for receiving the transmitted impulses, means controlled by the receiving means for

sending secondary impulses corresponding to the item to energize another relay of the comparing unit, means dependent upon whether the two energized relays of the comparing unit are in the same set or in different sets for determining whether primary impulses representing the selected item are to be retransmitted to the receiving means by a second operation of the transmitting means, and perforating means at the receiving station operated under the control of the receiving means upon the reception of the retransmitted primary impulses to perforate the selected item in a record.

7. In an item recording and verifying system, a transmitting station including therein transmitting means to transmit impulses representing a selected item; and a receiving station having therein a comparing unit including a plurality of sets of matching relays, receiving means operated by the transmitting means to receive said impulses, means controlled by the receiving means in accordance with the impulses received to energize a relay of one of the sets of relays in the comparing unit, means controlled by the receiving means to effect automatically a repeat operation of the transmitting means to send repeat impulses corresponding to the selected item to operate the receiving means to energize another relay of the comparing unit, perforating means for perforating the item in a record in accordance with the operation of the receiving means, means dependent upon whether the two energized relays of the comparing unit are in the same set or in different sets for determining whether the perforating means is to be operated in accordance with the receiving means following the reception of the repeat impulses from the transmitting station.

8. In combination, a transmitting station including therein transmitting devices for transmitting primary impulses corresponding to data and a primary comparing unit with a first section therein settable by and in accordance with the operation of said devices; a receiving and recording station remote from the transmitting unit and embracing receiving devices receiving and operated according to the transmitted impulses, a perforating mechanism to perforate the data represented by the impulses in a record, and also a secondary comparing unit with means operated by and according to the operation of the receiving devices for sending back secondary impulses corresponding to the digit values to the primary comparing unit; a second section in the latter comparing unit being responsive to said secondary impulses and coacting with said first section according to the setting thereof for causing a repeat transmission of the primary impulses to the secondary comparing unit, and means in the latter comparing unit responsive to the reception of repeated primary impulses for causing operation of the perforating means to be effected under control of and in accordance with the setting of said receiving devices.

9. In combination, a transmitting station embracing therein a uniformly rotating transmitting commutator, and a manual control device associated therewith adapted upon operation to cooperate with the commutator to transmit a predetermined number of control impulses; and a receiving station including therein a chain of relays responsive to said impulses and operated in succession thereby to an extent corresponding to the number of impulses received, a visual indicating means, an electromagnetic time delay

means set in operation by the first impulse received and effective at a subsequent time to cause the last relay energized at that time to become effective to operate the visual indicating means so as to indicate by a predetermined signal whether the time delay means became effective too early or too late, and adjustable control means for said time delay means arranged

for operation under the control of the transmitting commutator when the manual control device at the transmitting station is operated for obtaining a definite timed relation between the period of operation of the time delay means and the speed of rotation of the commutator. 5

JAMES W. BRYCE.
